[57] **CLAIM**

The ornamental design for a multi-compartment food holding cabinet, as shown and described.

DESCRIPTION

FIG. 1 is a front elevational view of a multi-compartment food holding cabinet showing my new design; FIG. 2 is a right side elevational view thereof, the left side elevational view being a mirror image of that shown;

FIG. 3 is a rear elevational view thereof;

FIG. 4 is a top plan view thereof;

FIG. 5 is a bottom plan view thereof; and,

FIG. 6 is a front and left side perspective view thereof.

FIG. 1

FIG. 2

FIG. 3

FIG. 4

FIG. 5

FIG. 6
